UNITED STATES PATENT OFFICE.

EMILE ANDREOLI, OF LONDON, ENGLAND.

APPARATUS FOR PRODUCING OZONE AND LUMINOSITY BY ELECTRICITY.

SPECIFICATION forming part of Letters Patent No. 565,952, dated August 18, 1896.

Application filed April 3, 1895. Serial No. 544,347. (No model.) Patented in France April 14, 1892, No. 221,176; in Belgium June 2, 1892, No. 99,236; in England November 14, 1893, No. 21,707; in Germany November 16, 1893, No. 77,925, and in Switzerland February 24, 1894, No. 7,997.

To all whom it may concern:

Be it known that I, EMILE ANDREOLI, a citizen of France, residing at London, in the county of Surrey, England, have invented certain new and useful Improvements in the Production of Ozone and Luminosity by Electricity, (patented by me in Great Britain November 14, 1893, No. 21,707; in France April 14, 1892, No. 221,176; in Belgium June 2, 1892, No. 99,236; in Germany November 16, 1893, No. 77,925, and in Switzerland February 24, 1894, No. 7,997,) of which the following is a full, clear, and exact description.

In my British patents, Nos. 17,426 of 1891, 15 9,631 and 21,794 of 1892, and in my United States application, Serial No. 444,064, filed August 25, 1892, I have described a mode of producing ozone by means of the silent discharges generated by an electric current from 20 points, sharp angles, asperities, and the like.

The object of the present improvement is the construction of ozonizers with vacuum-tubes in combination with electrodes, whereby ozone and luminosity or light are simultaneously produced. This is effected by the 25 use of such points, angles, asperities, or virtual edges as are afforded by serrated wires, fret-saws, or the like, in combination with vacuum-tubes or tubes containing more or less 30 rarefied gases, or with incandescent lamps, or other similar sealed dielectric vessels.

In the accompanying drawing the figure represents, somewhat conventionally, an apparatus comprehended by my invention.

The tubes *a* are provided inside with an 35 electrode *b*, consisting of a carbon filament or a metallic wire or rod, or several wires or rods, or with a bundle of small serrated wire, acting as an electrode, the points of which 40 radiate, so as to face the inside of the glass tube, or with any other convenient internal electrode. Outside the tube, and in proximity to it, either longitudinally, spirally, as shown, or otherwise, some serrated wires or 45 other equivalent metallic electrodes *c* are fixed in any suitable manner. One end of the wire, rod, or other electrode *b* contained in the vacuum-tube is connected with one of the poles of a Ruhmkorff coil *d*, or of a high-frequency

transformer. The external metallic electrode *c* of the tube is connected with the other pole and as soon as the electric current passes, the inside of the tube becomes luminous, and at the same time on each of the points of the serrated wires, fret-saws, &c., the characteristic glow of the silent discharge appears and is accompanied by a strong smell of ozone.

It is a well-known fact that the silent discharge produces a bluish or violet glow; but the luminosity of which I speak here is quite 60 distinct from the glow generated by the silent discharge. In my vacuum-tubes I have both the glow of the silent discharge outside, and what I call "luminosity" inside the tubes, and this combination not only has never been 65 patented before, but is scientifically a new phenomenon which differs as much from the disruptive discharge in ordinary vacuum-tubes as the internal luminosity of the tubes differs from their external glow, and, to the 70 best of my knowledge, nothing similar has ever been made before.

Having now particularly described and ascertained the nature of the said invention and in what manner the same is to be performed, 75 I declare that what I claim is—

An apparatus for the simultaneous production of ozone and luminosity or light which consists of point-bearing electrodes such as metallic serrated wires, points, &c., disposed 80 outside of, in close proximity to, but out of contact with a vacuum-tube, electric lamp, or similar device constructed of dielectric material, in combination with said tube, lamp or the like, internally provided with one or more 85 electrodes, and a source of high-frequency alternating currents, the terminals of which are connected respectively with the said electrodes outside and inside of said vacuum-tube, lamp, or the like, substantially as described.

In testimony whereof I subscribe my signature in presence of two witnesses.

EMILE ANDREOLI.
